By Jack Ashby Attorney

UNITED STATES PATENT OFFICE

JOHN W. STOKES, OF DALLAS, TEXAS

INCINERATOR

Application filed November 26, 1928. Serial No. 321,977.

This invention relates to new and useful improvements in incinerators.

One object of the invention is to provide in an incinerator separate compartments of novel arrangement whereby different kinds of garbage and trash can be burned at the same time.

Another object of the invention is to provide flues or openings in the partitions separating said compartments. These flues or openings are to be arranged in mismatched relation and located at the top, bottom or sides of these partitions so that regardless of how full each compartment is with burning material, suitable flues and proper draft will be provided.

Still another object of the invention is to provide sloping floors in each compartment having grates located therein, so that the garbage will more readily feed to said grates or may be raked thereon and also whereby ashes can be raked more easily into the grates.

A further object of the invention is to provide an auxiliary combustion chamber having a grate adjacent the outlet duct of the burning chamber next to same whereby an intense fire may be maintained for burning and melting cans and other material difficult to consume.

A still further object of the invention is to provide means whereby it is necessary for the gases and air currents escaping from the combustion chamber to pass through the grate of the last burning section to the smoke stack, so as to prevent burning material being drawn into the stack.

A construction designed to carry out the invention will be hereinafter described, together with other features of the invention.

The invention will be more readily understood from a reading of the following specification and by reference to the accompanying drawings, in which an example of the invention is shown, and wherein:

Fig. 1 is a horizontal cross-sectional view of an incinerator constructed in accordance with the invention,

Fig. 2 is a transverse vertical sectional view taken on the line 2—2 of Fig. 1,

Fig. 3 is a transverse vertical view taken on the line 3—3 of Fig. 1,

Fig. 4 is a reduced horizontal cross-sectional view taken on the line 4—4 of Fig. 3,

Fig. 5 is a reduced plan view,

Fig. 6 is an enlarged cross-sectional view taken on the line 6—6 of Fig. 5,

Fig. 7 is a vertical sectional view taken on the line 7—7 of Fig. 3, and

Fig. 8 is a reduced transverse vertical sectional view taken on the line 8—8 of Fig. 1.

In the drawings the numeral 10 designates the front wall, 11 the back wall, 12 the right side wall and 13 the left side wall of the main burning or combustion chamber of the incinerator. Within the chamber is an elevated floor 14 in which center grates 15 preferably of the rocker type, are set substantially flush. The burning chamber has an arch 17 spanning from the front to the back wall. An air space 18 is provided above the arch under a floor 19. Charging hoppers 20 mounted in the floor 19 extend through the arch so as to discharge onto the grates. Each hopper has a suitable closure 21.

The floor 14, as is shown in Figs. 2, 3 and 8, is downwardly inclined from the rear wall 11 to the grates 15 and is also downwardly inclined from the front wall 10 to the said grates. This gives a slight hopper effect to the floor so that refuse piled on the floor will tend to work toward the grates. Also the refuse or ashes therefrom may be readily raked onto the grates.

The burning chamber is divided into sections or compartments A, B, C and D by upright partition walls 16. Viewing Figs. 1 and 4, the section A is at the extreme right hand side of the structure, while the section D is at the extreme left hand side thereof.

An important feature of the invention resides in the draft openings in the partition walls 16. The section D (Fig. 3) has connection through its ash pit 31 with a transverse horizontal flue or duct 32 connected with a smoke stack 33. The products of combustion, such as gases and air currents, must pass from one section to another toward the section D and escape from the latter through the duct 32. If the refuse piled in a

100

section closed the opening to the next section, the draft would be cut off and combustion could not be maintained; also accumulating gases might result in considerable damage. In order to overcome these difficulties draft openings are located in the various partitions, as is shown in Figs. 2, 3 and 8.

In the partition between the sections A and B an opening 16' (Figure 3) is located at the top of said partition, while an opening 16a is located at the bottom thereof and these openings are offset laterally from each other. In the partition between the sections B and C (Figure 8) a top opening 160 is provided in offset relation to the bottom opening 16b. All the partition openings are offset laterally from each other so that the gases and currents will take a circuitous path and also so that at least one opening will at all times be open. This arrangement not only assures a draft but provides a better circulation. An enlarged discharge opening 25 connects the section C with the section D, thus assuring a free escape of the gases and currents into the section D.

Fire doors 22 are provided in the front wall for the various sections and under these doors ash doors 23 are arranged for raking out the ashes from the pits 24 and 31. The pit 31, which is under the section D, is somewhat longer than the other pits and extends back to the entrance to the flue 32. The other features are illustrated in my Letters Patent No. 1,570,531 issued January 19, 1926, and need not be described herein.

In operating the incinerator a fire is built on the grate 15 in the section A, but it could be built in either the section B or the section C if the preceding section was not to be used. The fire is started in any suitable manner with any suitable fuel. Garbage and refuse is dumped from the floor 19 through the charging hoppers, which being located directly over the grates 15 in the sections A, B and C will cause said garbage and refuse to be dumped onto said grates. However, the garbage and refuse will overflow the grates, but as the mass is consumed the inclined floor 16 will tend to cause the garbage and refuse to work down onto the grates. Of course the matter to be burned may be more readily raked onto the grates owing to the inclined floor. The ashes can also be easily pushed onto the grates and discharged into the pits below.

It is preferable to dump cans and other slow burning matter into the section C because the fire would be more intense in this section and also any unburned matter could be pushed through the duct 25 onto the grate in the section D. The staggered openings 16' will promote combustion and prevent retardation of the draft. This incinerator has been found to give excellent results in burning all kinds of garbage and refuse.

Various changes in the size and shape of the different parts, as well as modifications and alterations, may be made within the scope of the appended claims.

What I claim, is:

1. In an incinerator, the combination of a plurality of separate refuse burning sections separated by vertical partition walls having draft openings therein at the top and bottom thereof arranged in staggered relation, a flue leading from the burning section at one end of the incinerator, and a smoke stack connected with said flue. 70

2. In an incinerator, the combination of a combustion chamber divided into a plurality of burning sections by transverse vertical partitions, each partition having draft openings connecting the sections of said chamber, some of said partitions having draft openings at their tops and bottoms offset laterally from each other, grates located in each section of the combustion chamber, the floor of the combustion chamber in each burning section inclining from the front and rear walls toward the ends of the grates, a flue leading from the burning section at one end of the chamber, and a smoke stack connected with said flue. 80

3. In an incinerator, a combustion chamber divided into separate refuse burning sections by partition walls extending thereacross and from top to bottom thereof, and each partition provided with a top draft opening and a bottom draft opening offset laterally therefrom. 95

In testimony whereof I affix my signature. 100
JOHN W. STOKES.
